(57) **CLAIM**

The ornamental design for a ceiling fan light hood with motor housing, as shown and described.

DESCRIPTION

FIG. 1 is a top perspective view of a ceiling fan light hood with motor housing, showing my new design;

FIG. 2 is a bottom perspective view thereof;

FIG. 3 is a top view thereof;

FIG. 4. is a bottom view thereof; and,

FIG. 5 is a side view thereof.

Portions of the ceiling fan light hood with motor housing are shown in broken lines. Portions shown in broken lines form no part of the claimed design.

1 Claim, 5 Drawing Sheets
